MATTRESS

Ernest L. Basner, Barrington, Ill., assignor to Sealy,
Incorporated, Chicago, Ill., a corporation of Delaware

Filed Mar. 6, 1969, Ser. No. 16,082

Term of patent 14 years

Int. Cl. D6—01

U.S. Cl. D5—2

FIG. 2

FIG. 1 is an end, top and side perspective view of a mattress showing my new design, the opposite end and opposite side being substantially a mirror image of the end and side shown; and

FIG. 2 is a top plan view thereof, the bottom being substantially a mirror image thereof.

I claim:

The ornamental design for a mattress, substantially as shown and described.
